FINGER RING WITH KEY

Herbert H. Boscowitz, New York, N. Y.

Application March 6, 1946, Serial No. 652,277

11 Claims. (Cl. 63—1)

1

This invention relates to improvements in finger rings or other articles of jewelry intended for wearing as ornaments, and having a key for a lock attached thereto for instant and convenient use either for the ordinary operation of the lock, or more particularly for emergency use in cases where the regular key has been lost or mislaid. For example, the improved ring with combined key finds an important use as a combined ignition switch key and door key for automobiles, and is handy and useful in cases where the ignition key has been left in the ignition switch and the door of the automobile locked with an automatic spring lock or the like, so that the operator is unable to get the key from the ignition switch to unlock the door.

It is a general object of the invention to provide a finger ring or other similar article of jewelry, with an improved structure for carrying or supporting a key whereby the latter is instantly available for use to operate a lock and can be retracted into inoperative position.

A further object of the invention is to provide an improved structure of a combined finger ring and key whereby the key is concealed within the ring structure, as for example at the inner side of the band or bezel and held in such position so as to avoid interference with or marring of the decorative features of the ring, and to avoid any inconvenience to the wearer.

A further and more particular object of the invention is to provide in a combined finger ring and key structure, an improved mounting for slidably supporting the key in housed and concealed inoperative position in the ring structure and for being quickly and easily projected into operative position when the ring is removed from the finger, and held in retracted inoperative position when the ring is on the finger.

According to another improved feature of the invention, the key is mounted in the ring band and provided with a holding device adjustable thereon for cooperation with the ring to hold the key both in its retracted inoperative position and in its projected operative position, thus preventing accidental retraction or wrong positioning of the key during use thereof in operating the lock.

Another object is to provide an improved mounting whereby the key can be quickly and easily installed in operative position on the ring, quickly and easily removed.

Other objects of the invention will be in part pointed out in the following detailed disclosure of an illustrative but preferred embodiment of the invention, and will be in part obvious as the disclosure proceeds.

The invention accordingly comprises the features of construction, combination of elements, and arrangement of parts, which will be exemplified in the construction hereinafter set forth and

2

the scope of the application of which will be indicated in the claims.

For a more comprehensive disclosure of the nature, objects and advantages of the invention, reference is had to the following detailed description and to the accompanying drawings, in which:

Fig. 1 is an enlarged perspective top view of a finger ring carrying a key arranged in accordance with the invention, the key being in projected operative position;

Fig. 2 is an enlarged perspective view similar to that of Fig. 1 showing the bottom or underside of the structure, the key being projected and held in operative position;

Fig. 3 is a perspective view similar to Fig. 2 showing the key retracted and held in inoperative position;

Fig. 4 is an enlarged transverse section taken substantially on the line 4—4 of Fig. 2 looking in the direction of the arrows;

Fig. 5 is an enlarged section taken substantially on the line 5—5 of Fig. 3 looking in the direction of the arrows;

Fig. 6 is an enlarged transverse detail section showing the connection between the key and holding member; and

Fig. 7 is a fragmentary enlarged end elevation.

Referring to the drawing for a detailed description of the illustrative embodiment of the invention there shown, the improvements are embodied in a ring 10 of the signet type ordinarily of precious metal and having a finger band 11 and an enlargement 12 providing a bezel which may be adapted to carry decorative features such as a letter or monogram engraved on or attached thereto, or to carry a stone or other ornamentation. Although the invention as disclosed is applied to a ring of the signet type, it will be understood that it may be applied to other types of rings such as plain band rings or to other similar articles of decorative jewelry. The band 11 where it joins the bezel 12 is provided with an enlarged portion of gradually increasing cross sectional area from the band portion to the bezel portion as indicated at 13.

At the inner side of the enlarged portion or bezel 12 a supporting slideway is provided which in the embodiment shown is in the form of an elongated channel or groove 14. This groove 14 may be cut or cast into the inner surface of the bezel extending transversely of the latter and opening through one end of the bezel and closed at the other end thereof by means of an integral end wall portion 15, the outer surface of which ordinarily forms the outer end surface of the bezel. This elongated groove may be of any preferred cross sectional shape, being shown as substantially rectangular in transverse cross section and having substantially smooth bottom and side walls.

Extending transversely of the channel or groove 14 is a bar 16 positioned near the open end of the groove and some distance above the bottom thereof so as to form a keeper as later more fully described. As shown, this keeper bar is preferably made integral with the inner part of the ring bezel although in some cases it may be made of a separate detachable part.

The key 17 is mounted in the channel or slideway 14 for longitudinal sliding movements therein into extended operative position, and for retraction into inoperative position in which it is effectively supported and concealed in such a manner as not to interfere with the external appearance of the ring, and so as to avoid interference with the proper fitting of the ring upon the finger. This key 17 is the member adapted for operating the lock and may be of any desired construction and design for cooperation with known standard lock mechanism, as for example an ignition switch lock for an automobile and/or the lock for an automobile door. In the embodiment shown the key 17 is positioned to underlie the keeper bar 16 which serves as a guiding and retaining member for the key in its longitudinal sliding movements in the slideway 14. The key and other parts of the ring are preferably constructed of metal.

As best shown in Figs. 4, 5 and 6, a retaining or holding member or plate 18 is pivotally connected by means of a pin 19 engaging supporting knuckles 20 formed at the adjacent end portions of the key 17 and the holding member or detent 18. Thus the holding member 18 is swingably supported upon the key into position to overlie the key when the latter is in retracted inoperative position as shown in Figs. 3 and 5, or into extended position substantially in longitudinal alignment with the key when the latter is extended in operative position as shown in Fig. 4. The key 17 and the auxiliary controlling member or detent 18 form a key unit slidably adjustable in the slideway 14. When this detent or auxiliary member 18 is adjusted to overlie the key and to retain it in its retracted position as shown in Figs. 3 and 5 and in broken lines in Fig. 4, it forms a cover for the channel whereby the inner surface of the ring is substantially continuous across the channel.

Inwardly extending retaining flanges 21 are formed on the ring band along the inner side of the channel 14 in position to overlie the opposite ends of the pivot pin 19 and pivot knuckles 20 so as to retain the key 17 in its normal operative position in the slideway during longitudinal sliding movements thereof. These flanges 21 are cut away at end portions thereof so as to form entrance passageways 22 through which the end portions of the pivot pin 19 and the pivot knuckles 20 pass when assembling the key into its normal operative position in the slideway, or during removal thereof from the slideway. The retaining flanges 21 engage the pivot knuckles 20 during longitudinal sliding movements of the key 17 thus assuring smooth sliding movements.

At its free swinging end the holding member 18 is formed with a narrow integral centrally disposed extension 23 projecting only slightly at the adjacent outer surface of the ring and forming a handle engageable by the user for releasing the holding member 18 from holding positions; this may be done by means of an appropriate instrument or by the finger nail. A seat 24 is provided in the upper edge portion of the end wall 15 for receiving this handle 23, and a similar seat 25 is

provided in the upper portion of the keeper bar 16 for receiving this handle when the retaining member is positioned in its opposite holding position. The lateral surfaces of the seats 24 and 25 and also the inner surfaces of the end wall 15 and of the keeper bar 16 are formed to engage in close holding relation with the swinging end of the holding plate 18 and with the handle 23 thereof. These surfaces may be undercut slightly so

10 that the holding plate engages therewith with a snap fit to retain the holding plate in either of its holding positions, or the holding plate may be held in its holding positions merely by tight frictional engagement of the end portions thereof and 15 of the handle 23 with the engaging surfaces of the seats 24 and 25 and of the end wall 15 and the keeper 16.

When it is desired to use the key to operate a lock, the ring is removed from the wearer's finger 20 and the auxiliary plate or detent 18 released from its normal closed position, as shown in Figs. 3 and 5. This may be done by engaging the handle 23 with the finger nail or any appropriate implement such as a coin, and lifting the holding plate 18 from its retained position in the retaining seat 25 and swinging it upon its pivot 19. During this movement the key 17 can be slid outwardly from its retracted inoperative position through the opening 26 beneath the keeper bar 16. This opening 26 as shown preferably conforms to the cross sectional shape of the key so as to receive the latter closely and to support and guide it in its longitudinal movements, and also to support the key in operative extended position for use in the lock 30 as clearly shown in Fig. 4. During this extension of the key from retracted position to extended operative position, it is guided and supported in its sliding movements both by engagement of the key in the aperture 26 and by engagement of the 35 outer pivot knuckles 20 in the channel or slideway 14 beneath the overhanging flanges 21. Thus the key is so supported for sliding movements during extension or retraction thereof as to avoid any binding or obstruction, and also it is firmly supported in its extended position whereby it can be directed accurately to enter the lock in operative position therein. The key is stopped or limited in its outward movement by engagement of the pivot knuckles with the inner surface of 40 the keeper bar 16.

When the key is thus extended, it is supported and held in its extended position by the holding plate or detent 18 which is swung on its pivot substantially into longitudinal alignment with the key, extending inwardly from the end thereof 55 as shown in Fig. 4. The free swinging end of the detent is pressed downwardly into engagement with the seat 24 in the wall 15 where it is held by frictional engagement of the surfaces of the seat and wall 15 with the edges of the detent and handle 23. Thus the detent, being of stiff material such as metal, holds the key in its extended operative position, avoiding accidental retraction thereof during insertion in the lock and during the operation of the latter. The detent may be released from this position in the same manner as above described whereupon it is swung back again to its original position overlying the key when retracted into the position shown in Fig. 5. 60 In this retracted position the detent provides an effective cover plate for the top or inner side of the channel 14 so as to form a nearly continuous inner surface of the ring across and beyond the channel as best seen in Fig. 3.

The provision of the entrance passageways 22

through the flanges 21 at the inner end of the channel 14 enables a key with its pivotally connected detent 18 to be quickly and easily installed in operative position in the ring or to be removed from operative position therein. When installing the key, its free end is first placed in alignment with the aperture 26 and the pivotal knuckles 20 then lowered through the passageways 22 while the end of the key is moved forwardly slightly beneath the keeper bar 16 whereupon the free end of the detent is snapped into locking position in the locking seat 25, as shown in Fig. 5, and the ring is ready to be worn. When the key is thus assembled in its retracted position, it is housed in the ring structure and there is practically no alteration or marring of the external surface or appearance of the ring. Also the key is firmly and effectively supported both in its inoperative retracted position and in its extended operative position.

Since certain changes may be made in the above construction and different embodiments of the invention could be made without departing from the scope thereof, it is intended that all matter contained in the above description or shown in the accompanying drawing shall be interpreted as illustrative and not in a limiting sense.

The invention having thus been fully described, the following is claimed:

1. In a finger ring, in combination, a ring band having an elongated channel forming a slideway opening at the inner side of said band, a key supported in said slideway and slidable therein for extension into operative position and for retraction into inoperative position, and a holding member movably connected to said key and engageable in one position thereof with the ring to hold the key in retracted inoperative position and engageable in another position thereof with the ring to hold the key in extended operative position.

2. In a finger ring, in combination, a ring band having an elongated channel forming a slideway opening at the inner side of said band, a key supported in said slideway and slidable therein for extension into operative position and for retraction into inoperative position, and a holding member pivotally connected to said key and swingable thereon into different holding positions to hold the key either in retracted inoperative position or in extended operative position.

3. In a finger ring, in combination, a ring band having an elongated channel forming a slideway opening at the inner side of said band, a key supported in said slideway and slidable therein for extension into operative position and for retraction into inoperative position, and a holding plate pivotally connected to an end portion of said key and swingable thereon into position to form a cover for said channel overlying the key when retracted and engaging the ring to hold the key in its retracted inoperative position.

4. In a finger ring, in combination, a ring band having an elongated channel forming a slideway opening at the inner side of said band, a key supported in said slideway and slideable therein for extension into operative position and for retraction into inoperative position, and a holding member pivotally connected to said key and swingable thereon into position overlying the key and into engagement with the ring adjacent to one end of said channel to hold the key in retracted inoperative position, said holding member also being swingable into engagement with

the ring adjacent to the opposite end of said channel to hold the key in extended operative position.

5. In an article of jewelry, in combination, said article having an elongated channel opening at one side thereof, a key slidably mounted in said channel for longitudinal extension and retraction, and a plate connected to said key and forming a cover plate for said channel, said cover plate forming a holding device for retaining the key against longitudinal movements.

6. In an article of jewelry, in combination, said article having an elongated channel opening at one side thereof, retaining seats one of which is positioned adjacent to each of the opposite ends of said channel, a key slidably mounted in said channel for longitudinal extension and retraction, and a plate connected to said key and forming a cover plate for said channel, said plate forming a holding device movable into engagement with one of said seats to hold the key in retracted position or into engagement with another of said seats to hold the key in extended operative position.

7. In an article of jewelry, in combination, said article having an elongated channel opening at one side thereof, retaining seats one of which is positioned adjacent to each of the opposite ends of said channel, a key slidably mounted in said channel for longitudinal extension and retraction, and a key retaining member pivotally connected to said key and swingable into engagement with one of said retaining seats to retain the key in retracted position or into engagement with another of said seats to retain the key in extended operative position.

8. In a finger ring, in combination, a ring band having an elongated slideway and having at its inner side an opening to said slideway, a key unit adjacent to and operatively accessible through said inner opening and supported in said slideway for sliding movements into extended operative position and into retracted inoperative position, said key unit including a key and an auxiliary member, and a pivotal connection between adjacent end portions of said key and said auxiliary member connecting them together for relative pivotal movements into relatively longitudinally extended position when the key is projected into operative position or into relatively overlapping relation when the key is retracted into its inoperative position.

9. In a finger ring, in combination, a ring band having an elongated slideway and having at its inner side an opening to said slideway, a key unit adjacent to and operatively accessible through said inner opening and supported in said slideway for sliding movements into extended operative position and into retracted inoperative position, said key unit including a key and an auxiliary member, a pivotal connection between adjacent end portions of said key and said auxiliary member connecting them together for relative pivotal movements into relatively longitudinally extended position when the key is projected into operative position or into relatively overlapping relation when the key is retracted into its inoperative position, and a locking device for holding said key unit in its retracted inoperative position and set into locking position when said key and said auxiliary member are in their said overlapping relation.

10. In a finger ring, in combination, a ring band having an elongated slideway and a key unit supported in said slideway for movements into

extended operative position and retracted inoperative position, said key unit including a key and an auxiliary member, a pivotal connection between adjacent end portions of said key and said auxiliary member connecting them together for relative pivotal movements into relatively longitudinally extended position when the key is projected into operative position or into relatively overlapping relation when the key is retracted into its inoperative position, and spaced locking formations on said ring band cooperating with said auxiliary member of said key unit for holding said unit in its operative or inoperative positions.

11. In a finger ring, in combination, a ring band having an elongated slideway and having at its inner side an opening to said slideway, a key unit adjacent to and operatively accessible through said inner opening and supported in said slideway for sliding movements into extended operative position and into retracted inoperative position, said key unit including a key and an auxiliary member, a pivotal connection between adja-

cent end portions of said key and said auxiliary member connecting them together for relative pivotal movements into relatively longitudinally extended position when the key is projected into operative position or into relatively overlapping relation when the key is retracted into its inoperative position, and a locking formation on said ring band cooperating with said auxiliary member when the latter is in its said longitudinally extended position to hold said key in its projected operative position while the end portion thereof is engaged and supported in said slideway.
